(57) **CLAIM**

The ornamental design for a light-blocking window element, as shown and described.

DESCRIPTION

FIG. 1 is a front perspective view of a light-blocking window strip element showing the new design;

FIG. 2 is a rear perspective view thereof;

FIG. 3 is a right side view thereof;

FIG. 4 is a left side view thereof;

FIG. 5 is a top view thereof, a bottom view being a mirror image thereof;

FIG. 6 is a front side view thereof;

FIG. 7 is a rear side view thereof;

FIG. 8 is a front perspective view thereof, showing an alternate position;

FIG. 9 is a rear perspective view thereof, showing an alternate position; and,

FIG. 10 is a top view thereof, showing an alternate position.

The break lines shown in FIGS. 1-4 and 6-7 symbolize breaks in the length of the article in which the claimed design is embodied. The appearance of any portion of the article between the break lines forms no part of the claimed design.
